UNITED STATES PATENT OFFICE.

EARL R. PERRY, OF WORCESTER, MASSACHUSETTS.

CONCRETE-FORM CLAMP.

Application filed December 29, 1922. Serial No. 609,681.

To all whom it may concern:

Be it known that I, EARL R. PERRY, a citizen of the United States, residing at Worcester, in the county of Worcester and State of 5 Massachusetts, have invented a new and useful Concrete-Form Clamp, of which the following is a specification.

This invention relates to a clamp for tightening up and holding forms for the 10 molding of concrete. It is capable of being used for forms of any desired kind and character and as a clamp for general purposes.

The principal objects of the invention are 15 to provide a clamping device for one end of a rod of such a nature that it will consist of two parts only that are duplicates and can be made in the same mold if formed of cast metal; to avoid the use of screw 20 threads or other finished parts and provide a construction which will work quickly and will require a minimum manipulation and will hold the rod firmly in any position to which it may be brought by the clamping device.

Reference is to be had to the accompanying drawings, in which

Fig. 1 is a horizontal sectional view of 25 a part of a concrete mold showing a preferred form of this invention applied thereto;

Fig. 2 is a side elevation of the same;

Fig. 3 is a full size view of one of the 30 parts of the clamp; and

Fig. 4 is an end view of the same.

The invention is shown as applied to a rod 10 which may have a head or nut on one end and is to be tightened up at the other end by this device. The clamping device 40 consists of two collars 11 made alike in all respects, reversed, and placed end to end on the rod. One end of the rod being arranged in any desired way so that it cannot pull through the mold, the other end is 45 drawn up by my improved clamp. Each part of this collar 11 comprises a main body which has on the end a cam surface 12 sloping gradually and uniformly throughout a complete circle with an abrupt drop 50 or termination at 13. Near the other end this member is provided with a square, hex, or other shape 14 on which a wrench can be applied for operating the device. It is also provided with a passage 15 therethrough, 55 this passage being semi-circular at both ends and having the two semi-circles con-

nected by diverging walls so that it is of a general triangular shape. The object of this shape is to secure a wedging action and to permit of the device being used on 60 rods 10 of different sizes. For clamping the collar in place on the rod a set screw 17 or the like is used.

It will be understood that two of these 65 clamps are placed on the rod end to end reversed with the two cam surfaces 12 in contact, as shown at the right in Fig. 2. Although only one set of these clamps would be used on a single rod, I have shown two 70 of them in this figure to illustrate the clamping action. The one at the left shows the device in its clamping position, while the one at the right shows it in its original position and of course two of them could be used in that way instead of an ordinary 75 nut or head on the end of the rod.

In using the device, the clamping head 80 that is nearest the frame or wall of the form is located on it by tightening its set screw 17 lightly with the fingers. Then the 85 other collar is set up close to it, as shown at the right in Fig. 2 and its set screw 17 tightened up tight with a wrench. The first set screw can then be loosened if too tight but ordinarily being tightened by the fingers it can be left that way. It is merely tightened to prevent rotation on the rod. Then the operator places a wrench on the hex at 90 14 nearest the form and turns it to force the cams apart. This pulls the rod through 95 the inner collar and forces the other collar outwardly away from the form. The set screw in the collar nearest the form is then tightened up tight with a wrench and the outer collar removed.

This constitutes a powerful clamp for this 100 purpose and provides for the construction of the complete clamp by the use of only one mold, the two parts of the clamp being duplicates. It eliminates the ordinary 105 screw threaded arrangements, cams, and levers and the like which are commonly used. It provides for the use of a single size of clamping head with three or more sizes of wire rods and saves a great deal 110 of time in the clamping of the forms as well as in the manufacture of the device.

Although I have illustrated and described only a single form of the invention, I am aware of the fact that modifications can 110 be made therein by any person skilled in the art without departing from the scope of the

invention as expressed in the claims. Therefore, I do not wish to be limited to all the details of construction herein shown and described, but what I do claim is:—

5. 1. As an article of manufacture, a form clamp comprising two identical collars adapted to be received on a rod to be held, said collars being arranged right and left handed on the rod and having co-acting 10 adjacent cam surfaces on their ends, the collar which is nearest the form, between that and the outer one, being adapted to be turned on the rod to force the outer collar outwardly and hold the rod firmly.

15. 2. As an article of manufacture, a collar

for clamping the rod of a concrete mold form consisting of a device having a cam-shaped end and the other end of polygonal form and having a passage therethrough from one end to the other for the rod, and 20 means for clamping it to the rod.

3. As an article of manufacture, a collar for clamping a rod having a longitudinal passage therethrough larger at one side than at the other side, and means for clamping the collar to the rod, said collar having a cam-shaped end for the purpose described.

In testimony whereof I have hereunto affixed my signature.

EARL R. PERRY.
